PHILIP BERNARD, OF SIOUX CITY, IOWA.

RAIN-WATER FILTER.

1,130,663.

Specification of Letters Patent.

Patented Mar. 2, 1915.

Application filed April 20, 1914. Serial No. 833,216.

To all whom it may concern:

Be it known that I, PHILIP BERNARD, a citizen of the United States, residing at Sioux City, in the county of Woodbury and State of Iowa, have invented a new and useful Rain-Water Filter, of which the following is a specification.

The invention relates to improvements in rain water filters.

10 The object of the present invention is to improve the construction of rain water filters and to provide a simple, practical, and efficient non-freezing rain water filter of strong, durable, and inexpensive construction, 15 adapted to be easily cleaned and maintained in a perfectly sanitary condition.

With these and other objects in view the invention consists in the construction and novel combination of parts hereinafter fully 20 described, illustrated in the accompanying drawing, and pointed out in the claims here- 25 to appended, it being understood that various changes in the form, proportion, size and minor details of construction, within the scope of the claims, may be resorted to without departing from the spirit or sacrificing any of the advantages of the invention.

In the drawing: Figure 1 is a vertical 30 sectional view of a rain water filter constructed in accordance with this invention. Fig. 2 is a horizontal sectional view on the line 2—2 of Fig. 1. Fig. 3 is a horizontal sectional view on the line 3—3 of Fig. 1. Fig. 4 is a horizontal sectional view on the 35 line 4—4 of Fig. 1. Fig. 5 is a detail view illustrating the manner of closing the outlet when cleaning the filter.

Like numerals of reference designate corresponding parts in all the figures of the 40 drawing.

In the accompanying drawing, in which is illustrated the preferred embodiment of the invention, the filter comprises in its construction an outer casing 1, preferably of 45 cylindrical form and constructed of galvanized sheet metal or other suitable material, and provided with a downwardly tapered or conical bottom 2 having a central drain or cleanout opening 3 and an eccentrically arranged outlet 4 for the discharge of 50 the filtered water. The outlet 4 consists of a short vertical tube projecting interiorly and exteriorly of the outer casing and designed to have its outer portion connected 55 to a suitable conduit 5, as illustrated in dotted lines in Fig. 1 of the drawing, for

conveying the filtered water to a cistern or other reservoir (not shown). The bottom 2 is provided at the drain opening 3 with a depending threaded flange, and is equipped with a screw cap 6. When cleaning the filter, the outlet 4 is closed by a cap or closure 7, which is placed on the upper end of the outlet, and when it is desired to drain off any water used in washing the filter, the screw cap 6 is removed. By this arrangement the outer casing may be thoroughly cleaned 60 without any of the water used in cleaning passing out through the outlet 4 and entering the conduit 5.

The outer casing, which has a removable top or cover 8, is provided at the upper portion with an elbow pipe connection 9, designed to be connected with a rain spout 10, or other pipe connection, as indicated in 70 dotted lines in Fig. 1 of the drawing. The inlet 9, formed by the elbow, is located a short distance below the top or cover, and the water entering at the inlet 9 flows into an inner cylindrical casing 11 constructed 80 of galvanized sheet metal or other suitable material, and preferably consisting of a cylinder, open at the top and bottom and supported upon the bottom of the outer casing.

The inner casing, which forms a receptacle for charcoal 12, or other suitable filtering material, is provided with upper and lower horizontal screens 13 and 14, spaced apart to form an intervening compartment for the filtering material. The lower screen 90 14 is permanently secured within the lower portion of the inner casing in spaced relation with the lower edge thereof, to leave a lower end space of chamber 15, which constitutes a water compartment. The upper 95 screen is adjustable within the inner casing to enable it to be fitted tightly against the charcoal for holding the same firmly in place. The upper screen is provided at its upper face with a reinforcing brace 16, consisting of a flat bar, suitably secured to the screen.

Centrally riveted or otherwise connected to the brace 16 is a locking bar 17, arranged at right angles to the brace and having upturned terminals 19 provided with 100 slots 20 for the reception of bolts 21. The slot and bolt connection between the bar 17 and the inner casing enables the upper screen to be adjusted to clamp the charcoal and hold the same tightly against the lower 110 screen. This is especially advantageous, as it enables the inner casing, with the filtering

material, when removed, to be inverted for washing and cleaning, without displacing the charcoal, which is thereby enabled to last longer than it would were it loosely placed between the upper and lower screens.

5 While the upper and lower screens or partitions are preferably constructed of woven wire, they may be made of any foraminous material.

10 The upper screen 13 is arranged in spaced relation with the upper edge of the inner casing, and the upper portion of the latter constitutes an open upper compartment or chamber 22 for the reception of a substantially cylindrical screen 23 consisting of a basket having a woven wire body and provided with an imperforate bottom 24 of sheet metal or other suitable material. The basket forms a receptacle for leaves or other 15 coarse trash accumulating within an eaves trough, and carried down by the rain water. The imperforate bottom of the basket or receptacle is spaced from the lower edges of the woven wire body portion to provide an intervening space between the bottom of the basket and the filtering material. The imperforate bottom is adapted to distribute the water which flows around the edges of the imperforate bottom and through the space 20 between the same and the upper screen 13, and the said bottom 24 is adapted to prevent a constant drop of the water in the same place on the filtering material.

The lower open end of the inner casing 25 fits around the inwardly projecting portion of the outlet 4, and the said inner casing is equipped at its upper portion with a pivoted bail 25, to enable the inner receptacle and its contents to be conveniently lifted from the outer casing. The pivoted bail is foldable 30 within the outer casing when the parts are assembled. In order to take care of any superfluous rain water, the inner casing is provided at the upper portion with a lateral outlet 26 consisting of a short pipe or tube 35 extending through an opening 27 in the outer casing, and located at a point slightly below the inlet 9. The inner casing is of less diameter than the outer casing, which 40 is sufficiently larger than the inner casing to permit the lateral outlet to be readily introduced into and removed from the opening 27. The lateral outlet is maintained in the opening 27 by a wedge 28 located at the 45 opposite side of the filter and interposed between the inner and outer casings and adapted to maintain the inner casing in proper position with relation to the inlet, so that the rain water will be delivered into 50 the open upper end of the inner casing.

60 What is claimed is:

1. A filter of the class described, including an outer casing having an upper inlet and provided with a substantially conical bottom having a centrally arranged drain

opening, said bottom being also provided with an eccentrically arranged outlet, means located within the casing for holding filtering material, and removable closures for the drain opening and the outlet.

70

2. A filter of the class described, including an outer casing having an upper inlet and provided with a substantially conical bottom having a centrally arranged drain opening, said bottom being provided with an eccentrically arranged outlet consisting of a tube projecting into the outer casing, a closure for the drain opening, a cap adapted to be placed on the upper end of the outlet tube for closing the same when 75 cleaning the filter, and means removably arranged within the outer casing for holding filtering material.

3. A filter of the class described, including an outer casing having an upper inlet 85 and a lower outlet, an inner casing open at the top and bottom and provided at points intermediate of its ends with spaced foraminous partitions forming a compartment for the reception of filtering material, 90 the lower partition being fixed and the upper partition being adjustable, a locking bar connected with the upper partition, and means for adjustably securing the terminals of the said bar to the inner casing. 95

4. A filter of the class described, including an outer casing having an upper inlet and a lower outlet, an inner casing having a compartment for the reception of filtering material and provided above the same 100 with an open upper portion or chamber arranged to receive water from the said inlet, and a removable open top receptacle arranged within the upper portion of the inner casing and having a portion of its exposed surface constructed of foraminous material to form a screen and another portion of the said surface constructed of imperforate material to prevent a direct passage of the water therethrough. 105

5. A filter of the class described, including an outer casing having an upper inlet and a lower outlet, an inner casing having a compartment for the reception of filtering material and provided above the same 115 with an open upper portion or chamber arranged to receive water from the said inlet, and a removable open top receptacle arranged within the upper portion of the inner casing and composed of foraminous side 120 walls and an imperforate bottom spaced from the lower edge of the body to provide an intervening space between it and the bottom of the chamber.

6. A filter of the class described including an outer casing having an upper inlet and a lower outlet, and an inner casing open at the top and bottom and arranged within the outer casing in position to receive water from the said inlet and having 125 130

a chamber or compartment for the reception of filtering material spaced from the upper end of the inner casing to provide an upper chamber, said inner casing being 5 provided at the upper portion below its upper edges with a lateral outlet communicating with the said upper chamber and extending through the outer casing to permit excess of water to escape from the said 10 compartment without overflowing the top of the inner casing.

7. A filter of the class described including an outer casing having an upper inlet and a lower outlet and provided below the 15 plane of the inlet with an opening, an inner casing open at the top and arranged within the outer casing to receive water from the inlet thereof and provided with a

lateral outlet located below the upper edges of the inner casing to permit excess of water to escape without overflowing the upper edges of the inner casing, the latter being also provided with means for holding filtering material and having an upper chamber with which the said outlet communicates, 25 and a wedge interposed between the inner and outer casings for retaining the said lateral outlet in the opening of the outer casing.

I testimony, that I claim the foregoing as 30 my own I have hereto affixed my signature in the presence of two witnesses.

PHILIP BERNARD.
